UNITED STATES PATENT OFFICE.

JAMES H. RAND, JR., OF TONAWANDA, NEW YORK.

INDEX.

1,386,203.

Specification of Letters Patent.

Patented Aug. 2, 1921.

Application filed May 17, 1917. Serial No. 169,212.

To all whom it may concern:

Be it known that I, JAMES H. RAND, Jr., a citizen of the United States, residing at Tonawanda, in the county of Erie and State 5 of New York, have invented a new and useful Improvement in Indexes, of which the following is a specification.

This invention relates to indexes of that kind in which index tabs or holders are applied to and project from the edges of card index guides or partitions, the leaves of books and the like to facilitate the manipulation of the guides or leaves.

One object of the invention is to provide 15 a practicable and desirable index tab or holder which is strong and durable, which covers and protects a removable index slip and enables the index slip to be readily inserted into and removed from the holder.

20 In the accompanying drawings:—

Figure 1 is a perspective view on a reduced scale of a card index provided with index guides and tabs embodying the invention.

25 Fig. 2 is a perspective view of several of the guides.

Fig. 3 is a fragmentary front elevation, full size, of one of the guides, showing the index slip partially withdrawn from its 30 pocket.

Fig. 4 is an enlarged section on line 4—4, Fig. 3.

Fig. 5 is a longitudinal section through the index tab.

35 Fig. 6 is a fragmentary rear elevation, full size, of the guide and index tab.

Fig. 7 is a section, enlarged, showing a tab of modified construction.

40 Fig. 8 is a front elevation, full size, of a detachable tab embodying the invention.

Fig. 9 is an enlarged section of the tab shown in Fig. 8, showing it applied to a guide.

45 A represents an index guide or device for card index systems or an analogous member, such as the leaf of a book and B represents an index tab or holder embodying the invention projecting from one edge of the guide. The guide may be made of relatively stiff cardboard or any other suitable material.

The index tab or holder consists of a body piece 10 which projects beyond the edge of

the guide, and a cover-piece of thin sheet celluloid or other suitable transparent material 11 which coöperates with the body-piece to form an open-ended pocket into which an index slip or label 12 is adapted to be inserted endwise. The body-piece is made of sheet metal or other suitable thin stiff material and it can be a piece formed on or secured to the guide so as to form a substantially rigid projection on the guide and thus enable the guide to be moved or manipulated by means of the tab. In the 55 construction shown in Figs. 1-6, the celluloid cover-piece 11 is folded over the upper edge of the body-piece 10 and the body piece, together with the two edges of the cover are permanently secured on the rear 60 side of the guide A by small metal eyelets 13 or other suitable fastenings. The outer portion of the tab preferably projects at an 65 inclination from the guide so that the matter on the index slip can be readily read 70 through the transparent front wall of the pocket. The body-piece of the tab is provided with a rib, bead or ridge 14 which extends lengthwise of the tab and provides a 75 shoulder at or slightly above the bend of 80 the tab against which the lower edge of the index slip is adapted to engage. This shoulder holds the index slip parallel with the edge of the tab and prevents it from slipping down and wedging between the 85 lower attaching portions of the body-piece and cover. This rib or shoulder also holds the front wall of the cover spaced from the front face of the body piece 10, and thus insures sufficient space in the pocket to enable 90 the index slip to be readily inserted and removed. 15 indicates the end portions of the body-piece which are bent forwardly at the open ends of the pocket sufficiently to prevent the unintentional dislodgment of the 95 index slip from the pocket.

The tab shown in Fig. 7, is constructed as above described except that the rear fold 16 of the celluloid cover piece 11^a is not fastened by the eyelets 13 but only extends 100 partway down the rear side of the body-piece, far enough to be retained by the fold in connection with the upper edge of the body-piece. 14^a is the rib or shoulder for the engagement of the lower edge of the 105 index slip.

Figs. 8 and 9 show a tab or holder substantially similar to that first described except that it is detachably secured on the guide or member A, for which purpose the 5 inner or attaching portion of the tab is slit vertically at 17 to provide attaching tongues 18 between which the upper edge of the guide is inserted. These tongues grip the guide between them with sufficient force to 10 properly retain the tab in place on the guide. The tab could be detachably secured on the guide A in any other suitable way. In this construction the celluloid cover 11^b can be secured to the body piece 10^b by eyelets or 15 other suitable fastening devices, such as employed for securing the parts of the tab to each other and to the guide in the other constructions described. The body-piece in this construction, as in the others is preferably provided with a guide or spacing rib 20 or shoulder 14^b at the lower edge of the index slip.

In all of the constructions described the tab is made strong and substantially rigid 25 with the guide by the body piece thereof fastened to the guide or member A and the celluloid cover or sheath can be made very thin since it is retained in form and relieved of strain by the rigid body piece. 30 Each of the constructions provides a pocket into and out of which the index slip can be easily slid.

I claim as my invention:—

1. An index tab comprising a relatively 35 stiff body-piece which projects from and is substantially rigid with a guide or the like, and a flexible transparent cover-piece which covers one side of the body-piece and is retained in shape thereby and forms therewith 40 a pocket for an index slip, said body-piece having a portion adjacent to one edge of said pocket which holds the cover spaced from the face of the body-piece to facilitate the insertion of the index slip.
- 45 2. An index tab comprising a relatively stiff body-piece which projects from and is substantially rigid with a guide or the like, and a flexible transparent cover-piece which covers one side of the body-piece and is retained in shape thereby and forms therewith 50 a pocket for an index slip, said body-piece having a ridge extending lengthwise thereof which holds the cover spaced from the face of the body-piece to facilitate the insertion and removal of the index slip.
- 55 3. An index tab comprising a relatively stiff body-piece which is constructed to be detachably secured substantially rigidly to a guide or the like and project therefrom, 60 and a transparent cover piece which is folded over one edge of the body-piece and forms therewith a pocket for an index slip, said body-piece having a portion adjacent to one edge of the pocket which holds the 65 cover spaced from the face of the body-

piece to facilitate the insertion and removal of the index slip.

4. An index tab comprising a relatively stiff body-piece which is adapted to be secured to and form a substantially rigid projection on a guide or the like, and a flexible transparent cover-piece which is folded over one edge of the body-piece and forms therewith a pocket for an index slip, and fastening devices passing through and securing 70 together the body-piece and two parts of the cover. 75

5. An index tab comprising a relatively stiff body-piece which projects from and is substantially rigid with the guide, and a 80 folded flexible transparent cover-piece which covers both sides of said body-piece and forms pockets at opposite sides thereof, and means securing the two parts of the cover to said body-piece. 85

6. An index tab comprising a body-piece of relatively stiff material having an inner attaching portion adapted to be secured to a guide or the like, and an outer portion which projects at an angle from the guide, 90 and a transparent cover-piece which forms with the body-piece a pocket for an index slip, said body-piece having a portion adjacent to one edge of said pocket which holds the cover spaced from the face of the 95 body-piece to facilitate the insertion of the index slip.

7. An index tab comprising a body-piece of relatively stiff material having an inner attaching portion constructed to engage and 100 detachably retain the tab on a guide or the like to form a substantially rigid projection on the guide, and a transparent cover-piece which forms with the body-piece a pocket for an index slip, said body-piece 105 having a portion adjacent to one edge of said pocket which holds the cover spaced from the face of the body-piece to facilitate the insertion of an index slip.

8. An index tab comprising a body-piece 110 of relatively stiff material adapted to form a substantially rigid projection on a guide or the like, and a transparent cover piece which forms with the body piece an open ended pocket for an index slip, said body-piece having a portion adjacent to one edge of said pocket which holds the cover spaced from the face of the body-piece to facilitate the insertion of an index slip, and angularly projecting portions at the ends of said 115 pocket for retaining the index slip in the pocket. 120

9. An index tab comprising a relatively stiff body-piece adapted to form a substantially rigid projection on a guide or the like, 125 a transparent cover-piece which forms with the body-piece a pocket for an index slip, securing means adjacent one side edge of said body-piece connecting said body-piece and said cover-piece to said guide, and a 130

raised portion on said body-piece between the securing means and the free side edge of said body-piece, said raised portion forming a stop to engage the edge of an index slip inserted in said pocket to prevent said slip from dropping down into the joint between said body-piece, cover and guide.

Witness my hand this 16th day of May, 1917.
